UNITED STATES PATENT OFFICE.

ALBERT W. MORSE, OF LONG ISLAND CITY, NEW YORK.

LIQUID AND GAS MIXER.

Application filed September 6, 1922. Serial No. 586,491.

To all whom it may concern:

Be it known that I, ALBERT W. MORSE, a citizen of the United States, and a resident of Long Island City, in the county 5 of Queens and State of New York, have invented certain new and useful Improvements in Liquid and Gas Mixers, of which the following is a specification.

This invention relates to improvements 10 in liquid and gas mixers, and particularly to devices in which the liquid to be mixed with a gas or gases is atomized by means of so-called "nebulizers", in which the atomizing effect is obtained by the direction of admission of the liquid into passages leading to a small swirling chamber to be discharged therefrom in a very fine mist or vapor, prior to mixing the same with the gases.

20 The invention is described and illustrated as applied to a liquid fuel burner of the externally mixing type, and it is one of the objects to provide such a burner with means which will permit the use of gas in connection with the fuel oil; another object is to provide an air supply to stimulate or boost the gas supply if its pressure be low, and to arrange for proper deflecting surfaces within the burner and away from 25 the outlet to properly and thoroughly mix the gas and air prior to discharging the same into the mist of fuel oil issuing from the burner; a further object is to so proportion the inlet and outlet openings that the 30 highest velocity is reached at the burner outlet with a resulting propagation of the flame to such an extent that ignition can occur only beyond the burner outlet, thereby effecting a much greater safety in operation than known heretofore.

Other objects of the invention will appear in the following specification in which a preferred embodiment of the mixing device is described.

45 The invention is illustrated by the aid of the accompanying drawing in which

Fig. 1 is a vertical, longitudinal, sectional view of the mixer;

50 Fig. 2 is a transverse, cross sectional, view taken along the plane of line 2—2 in Fig. 1; and

Fig. 3 is a cross sectional view along the plane of line 3—3 in Fig. 1.

55 Like characters of reference denote similar parts throughout the several views and the following specification.

10 is a casing having an end 11, cylindrical in shape, forming a mixing chamber 12, and being threaded exteriorly at 13 to receive a deflector cap 14 which is adapted 60 to be adjustably screwed onto the threaded end 13. 15 is a circular outlet opening in cap 14. The outer end of cap 14 is bevelled at 16 for deflecting purposes, as will be explained more fully hereafter.

65 Extending through chamber 12, concentrically and preferably integral therewith, is a fuel conduit 17, provided with a central duct 18. Its lower end is threaded to receive a fuel supply pipe 19. 20 is an enlarged upper end of conduit pipe 17, threaded interiorly to receive a nebulizer 21.

70 Nebulizer 21 is provided in its center with a hollow core 22, cylindrical in shape, called the swirl chamber. 23 is a plug screwed 75 into the lower part of nebulizer 21 for the purpose of closing chamber 22. At the top of chamber 22 and in its center is a small circular outlet opening 24. 25 and 26 are small drilled passages extending into the 80 nebulizer at the sides of chamber 22. 27 and 28 are ducts or inlet orifices joining the innermost ends of passages 25 and 26 with the upper part of chamber 22. These ducts are positioned so as to impinge the circumference of chamber 22 tangentially, as is shown in Fig. 3 and they are further slightly inclined towards the outlet end. 29 is a polygonal projection around the outside of the nebulizer 21, slightly larger than 85 the enlarged end of conduit pipe 17, to facilitate screwing the same into the pipe. The top of the nebulizer 12 is chamfered at 30, so as to make the outlet passage 24 as short as possible.

90 Extending at substantially right angles to the axis of chamber 12 and near its lower end is a tubular extension 31 of the casing 10 forming a passage 32. Its extreme end, away from the chamber 12, is 95 threaded interiorly for an air supply pipe 33, in communication with a nozzle 34, extending partially into passage 32 and having its walls converging toward chamber 12. Adjacent the air inlet connection of passage 100 32 and surrounding the nozzle 34 is an elbow shaped terminal 35 of the casing 10, threaded interiorly at substantially right angles to the air connection, to receive a gas supply pipe 36.

105 The operation of the device is as follows: Oil under pressure passes through con-

duit pipe 17 into the nebulizer 21 through passages 25 and 26 and from there through inlet orifices 27 and 28 into the swirl chamber 22. Owing to the direction of the inlet 5 orifices, tangentially with respect to the wall of chamber 22, the oil is being given a swirling motion and is finally expelled in form of a very fine mist from the outlet 24 where it assumes the shape of an inverted cone.

Gas is admitted through pipe 36 into passage 32, where it receives an impetus of air and is forced against the walls of conduit 18 and chamber 12. Being forced 15 against these walls at substantially right angles, the air and gas are thereby thoroughly mixed and finally forced out through the outlet 15, where by means of wall 16, they are deflected against the mist of oil 20 issuing from the nebulizer.

Outlet 15 being of smaller area than the combined area of the small diameter of the air nozzle 34 and the gas supply pipe, the mixture of gas and air issues from the outlet 25 at a very high rate of velocity. Due to this high velocity, the mixture of oil, gas and air is propagated to such an extent that ignition can occur only beyond the outlet, whereby the operation of the device 30 is made very much safer, it being impossible for the flame to back up into either the gas or fuel pipes.

It is obvious, of course, that if so desired, the device may be used for either burning 35 oil or gas, or both simultaneously; furthermore, if the gas pressure should be very high, the gas may be piped to the casing where the drawing shows the air pipe connected and the air to the gas connection. Furthermore, while the device has been described as being used as a liquid fuel or gas 40 burner, it may be used for any purpose which requires the mixing of several gases or liquids.

Various changes in the form, proportion 45 and minor details of construction may be resorted to without departing from the principle or sacrificing any of the advantages of the invention, as defined in the 50 appended claims.

What I claim as new, is:

1. In a liquid fuel and natural gas burner, a casing having one end cylindrical in shape forming a mixing chamber, a liquid fuel supply conduit extending 55 through the said mixing chamber and being in central alignment therewith, a nebulizer at the outlet end of the said conduit, a gas connection and an air connection, the

said air connection being provided with a nozzle converging toward the said chamber, and projecting into the said gas connection and being adapted to discharge air and gas into the said mixing chamber, and a cap at the end of the mixing chamber adapted to 60 deflect the mixture of air and gas against the liquid fuel issuing from the said nebulizer at a velocity sufficient to prevent back firing.

2. In a liquid and gas mixer, a casing 70 having one end cylindrical in shape forming a mixing chamber, a liquid supply conduit extending through the said mixing chamber and being in central alignment therewith, a nebulizer at the outlet end of the said conduit, a gas connection and an air connection, the said air connection being provided with a nozzle converging toward the said chamber and projecting into the said gas connection and being adapted to discharge air and gas into the said mixing chamber at a velocity greater than that due to the pressure head of the gas, and a cap having a central outlet at the end of the said mixing chamber, the 75 said outlet being of a smaller area than the combined area of the smallest diameter of the said converging nozzle and the said gas supply pipe.

3. In a liquid fuel and natural gas 80 burner, a casing having a mixing chamber, a liquid fuel supply conduit extending therethrough, a nebulizer at the outlet end of the conduit, a gas connection and an air connection, the said air connection being provided with a nozzle converging toward the said chamber and projecting into the said gas connection and being adapted to discharge a mixture of gas and air into the said mixing chamber at a velocity 85 greater than that produced by the element of the mixture under the least pressure, and a cap surrounding the said nebulizer, having deflecting surfaces so shaped as to discharge the mixture of gas and air against the liquid fuel issuing from the nebulizer and adjacent the said nebulizer, for the purpose of propagating the ignition point of the flame of the burner sufficiently ahead of its outlet to prevent back firing.

In testimony whereof I have hereunto set my hand and seal in presence of two subscribing witnesses.

ALBERT W. MORSE. [L.S.]
